UNITED STATES PATENT OFFICE.

JOSEPH OREA HENRI ROY, OF MONTREAL, QUEBEC, CANADA.

FITTING-FORM.

1,252,618.

Specification of Letters Patent. Patented Jan. 8, 1918.

Application filed December 2, 1916. Serial No. 134,686.

To all whom it may concern:

Be it known that I, JOSEPH OREA HENRI ROY, a subject of the King of Great Britain, and resident of 1172 Delorimer street, in 5 the city of Montreal, Province of Quebec, Dominion of Canada, have invented certain new and useful Improvements in Fitting-Forms, of which the following is the specification.

10 The invention relates to improvements in fitting forms as described in the present specification and illustrated in the accompanying drawings, that form part of the same.

15 The invention consists essentially of the novel shapes and arrangement of patterns and inflation bags, whereby the fitting form is readily adapted to persons of either sex or of mature or tender years in age.

20 The objects of the invention are to devise a form, which may be made individual to the person using it and continue to serve as a model for fitting and making the garments from time to time without the actual presence of the person, and generally to 25 provide a useful article that will, at a moderate initial expense, facilitate the cutting and finishing of wearing apparel.

In the drawings, Figure 1 is a front elevational view of the inflating member.

Fig. 2 is a vertical sectional view through the inflation member, casing and pattern.

Fig. 3 is a vertical sectional view taken at right angles to the view shown in Fig. 2.

25 Fig. 4 is a horizontal sectional view adjacent to the lower end.

Fig. 5 is a side elevational view of the complete form on a stand showing the box as support.

30 Fig. 6 is a plan view of a group of patterns.

Fig. 7 is an enlarged detail showing the fastening of the case to the edge of the base, showing the latter broken away.

45 Like numerals of reference indicate corresponding parts in each figure.

Referring to the drawings, the inflation bag 1 is preferably formed of air tight rubber cloth having little or no resiliency in the 50 material itself, the said bag in shape converging slightly from the hip portion 2 to the waist portion 3 and from said waist portion spreading to the shoulders 4, wider than said hip portion, and sloping upwardly and inwardly to the neck portion 5, the latter being slightly tapered and having a

valve orifice containing the air valve 6. The shoulder hooks 7 are secured in the rubber material at the extremities of the bag at said shoulders 4, the breast hooks 8 in the 60 front, one at each side, and similar hooks at the back, the hip hooks 9 just below the widest bulge in the bag in that portion, the hook 10 near the bottom at the front and a similar one at the back.

65

The bag thus made in this peculiar shape adapts itself readily to the various figures of men, women and children as the patterns determine the peculiarities of the figure and this shape of bag extends the patterns to 70 the contour of the person fitted notwithstanding any peculiarities of form.

The bag 1 is separated centrally just below the neck portion 5 by the elongated passage 11, which extends clear through 75 from front to back to enable the insertion of a pattern piece to draw in the bag to the corresponding depth of chest through to the back of the person to be fitted.

The seams all around this passage both at 80 the front and back and also through are perfectly air tight, so that the inflation of the bag is in no way interfered with.

The said passage 11 starts at the lower end of the breast and terminates at the 85 neck, consequently the chest is drawn in sufficiently to resemble closely the human form as it shapes inwardly to the neck and similarly the back is drawn in between the shoulder blades.

90

The case 12 is shaped similarly to the bag 1 and has a corresponding hole for the valve 6 in the neck portion 13 and at the bottom a band 14 in which are a number of hook holes 15. The eyes 16 correspond in number to the various hooks attached to the bag 1 and are secured to the inside of the case 12, so that the said bag 1 can be readily attached to the case 12 at all necessary parts before the said bag is blown up.

100

The base 17 is of oval shape and made of wood or metal or other suitable material and has projecting from the edge face the hooks 18 adapted to engage the eyes 16 of the case 12.

105

It is thus that the lower end of the form is shaped, for the bag 1 being firmly hooked to the case 12 and the latter hooked to the base 17, naturally the bag 1 will fill up the lower part of the figure just below the 110 hips.

The extensible and adjustable rod 19 is

screw threaded into the center of the base 17 in the underside at its upper end and at its lower end into the center of the box 20, which is intended to contain the parts in 5 their collapsed state.

The pattern piece 21 already mentioned generally is a tubular piece of textile material cut with a projecting downward point 22 at the back thereof lengthening the back 10 opening of the piece as compared to the front. This piece 21 is sewn to the case 12 at the front and back and extends through the passage 11 in the bag 1, thereby measuring permanently, while the set of patterns 15 are used, the depth of the chest from front to rear in the inflated bag to correspond precisely with the depth of the chest of the person measured.

The neck band pattern piece 23 encircles 20 the neck portion of the said case below the neck pattern piece 24. The front pattern pieces 25 are in pairs for the front of the form, and are cut to the person similarly to the pieces 21, 23 and 24, though intended to take in the front half of the 25 figure from just below the hips to the neck, including the groin, the hips, the abdomen, the waist, the breast and the shoulders. These pieces 25 have in the breast a com- 30 paratively short V-cut 26, below the breast a longer V-cut 27 and at the lower end a medium V-cut 28, these cuts being judged largely by the person measured.

The back pattern pieces 29 are cut similarly to measurement in pairs and include the posterior, the hips, the waist, the small of the back and the shoulders up to the neck, said pieces 29 having the V-cut 30 at the shoulders and the V-cut 31 at the bottom, 40 the latter with the cut 28 being used in drawing in the cloth of the patterns to the base 17 by means of the pattern piece 32 which is placed over the underside of said base.

45 The arm pattern piece 33 is tubular and is adapted to be sewn on at the shoulder and filled with a separate inflatable bag.

In the use of this fitting form, the patterns are first cut according to the measurements of the person for whom the form is 50 being prepared.

The patterns will if required be fitted on the person, so as to have them exact to

the figure, after that operation they are in readiness to be permanently secured over the 55 case 12 and base 17, the pattern 21 being first inserted within the case to regulate the depth of the chest.

The several patterns are securely sewn over the case 12 and remain permanently 60 there, so long as the person remains the same as to measurements, consequently the said person can leave the fitting form at any place for use during an absence as the presence of the person for the purpose of fitting is never required, because the form gives a precise reproduction of the body down to include the groins and posterior.

Various changes may be made in making this fitting form without departing from 70 the spirit of the invention, so long as they remain within the scope of the claim for novelty following.

It may be mentioned that the hooks attached to the bag are in each instance 75 strengthened by reinforcing straps, which also materially increase the strength of the bag at parts most necessary, also it has not been stated that the case 12 is of smaller dimensions than the bag 1 though of precisely similar shape, except as to the passage 11.

What I claim is:—

In a fitting form, an inflating bag having its greatest breadth at the shoulders and a 85 passage centrally therethrough extending from the lower end of the breast to the neck, a case inclosing said bag, completely, a tubular pattern piece having downward extension at the back and sewn to said case 90 at both front and back and passing through said central passage in the bag and permanently secured with each set of patterns, respectively, and a set of patterns of a lot including said tubular piece and in addition neck band, neck piece, arm piece, bottom piece, front pieces in duplicate clipped at bottom and breast and back pieces in duplicate clipped at shoulder and bottom.

Signed at the city of Montreal, Canada 100 this 13th day of November 1916.

JOSEPH OREA HENRI ROY.
